UNITED STATES PATENT OFFICE.

SAMUEL FUERSTENBERG, OF NEW YORK, N. Y., ASSIGNOR TO JULIUS WODISKA, OF SAME PLACE.

DESIGN FOR A TOOTHPICK-HOLDER.

SPECIFICATION forming part of Design No. 25,352, dated April 7, 1896.

Application filed March 3, 1896. Serial No. 581,712. Term of patent 7 years.

To all whom it may concern:

Be it known that I, SAMUEL FUERSTENBERG, a citizen of the United States, residing in the city, county, and State of New York, have invented and produced a new and original Design for Toothpick-Holders, of which the following is a specification.

The leading feature of my design is a toothpick-holder or analogous article of substantially the configuration and representation shown in the accompanying drawings, in which—

Figure 1 is a general perspective view of the toothpick-holder, and Fig. 2 is a central transverse section thereof.

In the drawings, A is the base of the toothpick-holder, which is curvilinear and terminates in a pillar B, terminating in a hollow container C for the toothpicks, which is slotted at c c and cut away to form finger-holes d e. The container terminates in caps f.

What I claim is—

The design for a toothpick-holder, substantially as herein shown and described.

SAMUEL FUERSTENBERG.
